UNITED STATES PATENT OFFICE.

THOMAS JAMES FOREMAN, OF SPECHT, OHIO.

ANIMAL-TRAP.

SPECIFICATION forming part of Letters Patent No. 734,413, dated July 21, 1903.

Application filed May 19, 1902. Serial No. 107,889. (No model.)

To all whom it may concern:

Be it known that I, THOMAS JAMES FOREMAN, a citizen of the United States, and a resident of Specht, county of Carroll, and State 5 of Ohio, have invented certain new and useful Improvements in Animal-Traps, of which the following is a specification, reference being had to the accompanying drawings, forming a part thereof, in which similar letters of 10 reference indicate corresponding parts.

This invention relates to animal-traps, the object thereof being to provide an improved device of this character which is of durable and simple construction and which is effective in general operation.

The whole device is composed of wire of a single gage, and it embodies spring-actuated members for simultaneous and automatic action in both a downward and a lateral direction for the purpose of effectually ensnaring the animal.

The invention will be hereinafter fully described, and specifically set forth in the annexed claims.

25 In the accompanying drawings, forming part of this specification, Figure 1 is a side elevation of my improved trap, showing the same set in full lines and sprung in dotted lines; and Fig. 2 is a plan view.

30 In the practice of my invention I employ primarily a spiral spring A, embodying any suitable number of coils. One terminal of this spring is extended to form the loop B, which embodies the top part b and the bow b', the terminal end of the bow having an elongated loop 1, which is coupled with an eye 2, forming part of the part b. The other end of the spring A is extended to form the presser-rod C, which is adapted to swing downwardly 35 by the tension of the spring to press the animal within the bow B. These parts are constructed of a single piece of resilient metallic wire.

40 Swinging within the loop 1 at the terminal end of the bow b' is the trip-pedal D, which is also composed of wire and embodies the elongated loop forming the pedal d, the eye d', which interlocks with the loop 1, and the hook d², which is adapted for engaging the 45 free end of the swinging latch-bar E. This bar acts to set the trap and also to choke or ensnare the animal. The latch-bar E is pivot-

ally attached by means of its eye e to an eye 3, formed on the part b of the loop B.

The presser-rod C has a loop c, forming 55 part thereof, which surrounds the bar E for the purpose of operating the device, as will be hereinafter described. The spring A is expansible, whereby the presser-bar C normally occupies the relative position indicated 60 by dotted lines, Fig. 1 of the drawings, the expansion being limited by reason of the loop c contacting with the bow b'.

In the operation and use of the invention when it is desired to set the trap the presser-rod C is forced against the tension of the spring into the position shown by full lines, Fig. 1 of the drawings. The latch-bar E is then locked within the hook d² of the trip-pedal D, with the loop d of the pedal extended 70 upwardly and surrounding the lower end of the bow b'. The trap is then placed in upright position contiguous to the inlet of an animal's burrow, so that the animal when passing in either direction through the loop 75 B is required to step on the pedal and by his weight trip the bar E, whereupon the action of the spring causes the rod C to rapidly move downwardly and by reason of its loop c carry the bar E toward the upright part of the 80 bow b, thus effectually ensnaring the animal.

The trap may also be used to catch rats, mice, or other vermin, and it may be baited by placing a small quantity of food upon the loop d of the pedal D.

I do not confine myself to the exact contour of the parts as herein shown and described, as it is obvious that under the scope of my invention I am entitled to slight variations.

Having now described my invention, what I claim as new, and desire to secure by Letters Patent, is—

1. In an animal-trap, the combination with the spiral spring having the vertical loop extended from one end thereof and the presser-bar from the other, the presser-bar having a lateral loop, of the latch-bar pivoted to an eye of the upper part of the said vertical loop and operating within the loop of the lateral 95 presser-rod, and the trip-pedal engaging an eye formed in the upper part of said vertical loop and having the hook for engagement with the latch-bar for locking the parts in set 100.

position, substantially as shown and described.

2. In an animal-trap, the combination with the spring A, the bow B, integral therewith formed with the elongated loop 1 and eyes 2 and 3, and arranged so that the elongated loop 1, rigidly engages with the eye 2, the presser-rod C, also integral with the said spring A, and formed with the loop c, and the latch-bar E, formed with the eye e, and arranged to engage the said eye 3 of the bow B therewith and also to extend through and be engaged by the loop c, of the presser-rod C, of the trip-pedal D, formed with the elongated loop d, embracing the lower part of

said bow, the eye d', and the hook d², arranged to interlock the said elongated loop 1, with its eye d', and with its hook d², to engage and hold the latch-bar E, and to release said bar, when pressure is applied to said loop d.

In testimony that I claim the foregoing as my invention I have signed my name, in presence of two witnesses, this 26th day of March, 1902.

THOMAS JAMES FOREMAN.
